INVENTOR.
Harry Cohen

BY Bennett H. Levenson,
ATTORNEY.

Patented June 24, 1941

Des. 127,938

UNITED STATES PATENT OFFICE

127,938

DESIGN FOR A BELT OR SIMILAR ARTICLE

Henry Cohen, New York, N. Y.

Application May 20, 1941, Serial No. 101,027

Term of patent 3½ years

To all whom it may concern:

Be it known that I, Harry Cohen, a citizen of the United States of America, residing in New York city, county of New York, and State of New York, have invented a new, original, and ornamental Design for a Belt or Similar Article, of which the following is a specification, reference being had to the accompanying drawing, forming part thereof.

Fig. 1 is a plan view of a belt or similar article showing my new design.

Fig. 2 is a cross sectional view taken at line 2—2.

I claim:

The ornamental design for a belt or similar article, substantially as shown.

HARRY COHEN.

CERTIFICATE OF CORRECTION.

Design No. 127,938.

June 24, 1941.

It is hereby certified that error appears in the above numbered patent requiring correction as follows: In the grant, lines 1 and 13, and in the heading to the printed specification, line 3, name of inventor, for "Henry Cohen" read --Harry Cohen--; and that the said Letters Patent should be read with this correction therein that the same may conform to the record of the case in the Patent Office.

Signed and sealed this 5th day of August, A. D. 1941.

(Seal)

Henry Van Arsdale,
Acting Commissioner of Patents.
